TOP FOR THE BED OF A PICKUP TRUCK

Millard M. Martin, 20892 Redwood Road,
Castro Valley, Calif.

Filed Jan. 6, 1961, Ser. No. 63,469

Term of patent 3½ years

(Cl. D14—27)

Fig. 1.

Fig. 2.

FIG. 2.

The truck fragmentarily shown in broken lines in FIGURES 1 and 2 is included for illustrative purposes only.

I claim:

The ornamental design for a top for the bed of a pickup truck, substantially as shown and described.
